EDWARD E. PARSONAGE, OF OAKLAND CITY, INDIANA

SCREEN

Application filed April 6, 1931. Serial No. 528,158.

My present invention has reference to a coal screen designed for use in coal mine tipplers, and my object is the provision of a screen for this purpose, that includes a number of 5 screen plates secured upon the angle sides of end members or heads which are centrally journaled on shafts that pass transversely through the screen-box, each of the plates being provided with series of apertures but 10 the apertures on the different plates varying in area so that coal of different sizes may be screened when the heads or end members are turned on the shafts to bring plates having the same size apertures therethrough in horizontal alinement, together with simple but 15 effective means for locking the heads and holding the turned plates in horizontal alinement, and whereby shaker or vibratory screens may screen coal of different size without necessitating the shutting down of the 20 screening plant and the loss of time incident to the removal of screens fixed on the screen box and replacing such screens with other screen plates to screen other sizes of coal. 25 The invention will be fully and comprehensively understood from a consideration of the following detailed description when read in connection with the accompanying drawings which form part of the application, with 30 the understanding, however, that the improvement is capable of extended application and is not confined to the exact showing of the drawings nor to the precise construction described and, therefore, such 35 changes and modifications may be made therefrom as do not affect the spirit of the invention nor exceed the scope thereof as expressed in the appended claim.

In the drawings:

40 Figure 1 is a top plan view of the improvement, the screen box being in section.

Figure 2 is a side elevation of the screen box with parts broken away and parts in section.

45 Figure 3 is a transverse sectional view approximately on the line 3—3 of Figure 2.

Figure 4 is a sectional view approximately on the line 4—4 of Figure 5.

50 Figure 5 is a sectional view approximately on the line 5—5 of Figure 4.

The screen box is indicated in the drawings by the numeral 1 and is of the usual construction. The box has series of longitudinally alining transversely arranged round openings 2 therethrough and these openings are surrounded by bosses 3. There are passed through the openings 2 shafts 4 and these shafts may be and preferably are connected to the agitating mechanism for the screen. 55

Arranged in the box 1, at the sides thereof, 60 there are the end plates or heads 5 of the improvement. The plates 5 are provided with central openings that are surrounded by bosses and through which openings the shafts 4 pass. Thus the plates or heads 5 are revolu- 65 bly mounted on the shafts 4.

In the showing of the drawings the heads or plates 5 are in the nature of triangular members with their points cut-away. The edges or ends of the members 5 are formed 70 with laterally extending flanges 6, the same being provided preferably by riveting angle plates 7 on the opposite faces of the members 5. There is riveted or otherwise rigidly secured to the laterally extending or widened 75 edges of the members 5 plates 8, respectively. All of these plates are of the same width and each of the plates is provided with series of apertures 9. The apertures, however, on the respective plates vary in size or area, but 80 those on the cooperating plates are of the same size.

Inward of the cut-away points of the triangular members 5, whose edges for distinction are indicated by the numeral 10, the 85 plates are provided with round openings 11, each of which is surrounded by a boss 12. The sides of the box 1 are provided with a series of spaced apertures, three in number, two of which being disposed in longitudinal 90 alinement above the openings 2 and the other directly below the said openings 2 and these openings are designed to register with the openings 11 in the end members 5 for the screen plates. The openings in the sides of the box are surrounded by bosses 13, and through these openings there are passed pins 14 which also enter the openings 11. The pins are held positioned through the medium of 95 cotter pins or like removable elements 15 100

which pass through the outer bosses 13 and likewise pass through openings in the headed pins 14.

With my improvement it is merely necessary to withdraw the cotter pins and the headed pins 14 to permit of the screens revolving on the shafts 4 to bring the desired screen plates into longitudinal alinement and with my improvement it will be apparent that 10 coal or three different sizes may be screened. The changing of the screens does not necessitate the shutting down of the screening plant and obviously avoids a great loss of time which is required to remove the ordinary 15 screen plates and to replace the same with other screen plates. The device is also, it will be noted, of an extremely simple nature.

Between the sides of the box 1 there are fixed substantially T-shaped brace members 20 16 whose central portions depend into the box but whose outer portion or head is arranged in a line with the outer faces of the screen plates 8. The brace members 16 are also disposed opposite the edges 10 of the end 25 plates or heads of the screens, permitting the screens to revolve therethrough. The heads of the members 10 prevent the passage of coal between the adjacent and cooperating screens.

30 While I have illustrated and described my invention in connection with the shaker screen for use in coal mine tipples, it is to be understood that the same may be connected with a vibrating or other agitating means 35 and that the improvement is not necessarily restricted as a screen for coal but may be employed with equal efficiency for screening cereals and other materials.

If desired, and as disclosed by Figure 3 of 40 the drawings, reinforcing triangular central plates 17 may be also mounted on the shafts 4 for more effectively supporting the screen plates 8.

Having described the invention, I claim: 45 In a device for the purpose set forth, a screen box having alining transverse shafts journaled therethrough, screens in the box centrally journaled on the respective shafts, each screen comprising end members which 50 are of triangular formation but which have their points cut-away, and their edges except at the cut-away portions thereof widened laterally, each of said members, inward of the cut-away portions having an opening surrounded by a boss, plates fixedly secured on the widened edges of the members, and each of said plates having a series of apertures therethrough, and the apertures on the respective plates varying in area, the sides of 55 the box having openings therethrough adapted to aline with the openings in the end members of the screen when the screens are turned on their shafts to bring certain of their apertured plates uppermost and in horizontal 60 alinement, said openings being surrounded 65

by bosses, headed pins passed through said alining openings to hold the screens from turning, removable means for securing the pins in the openings, and T-shaped braces between the sides of the box having their upper and widened portions in a line with the horizontally arranged screen plates and arranged between the confronting cut-away portions of the horizontally disposed screen plates and at the outer cut-away portions of the said screen plates.

EDWARD E. PARSONAGE.
